UNITED STATES PATENT OFFICE.

JAMES W. HENTZ, OF BALTIMORE, MARYLAND.

CLOSURE FOR BOTTLES, JARS, &c.

1,284,332.

Specification of Letters Patent. Patented Nov. 12, 1918.

Application filed October 1, 1914. Serial No. 864,395.

To all whom it may concern:

Be it known that I, JAMES W. HENTZ, a citizen of the United States, residing at Baltimore, State of Maryland, have invented a new and useful Improvement in Closures for Bottles, Jars, &c., of which the following is a specification.

This invention relates to improvements in closures for bottles, jars, &c., and has for its object to provide means integral therewith by means of which the closure can be readily removed from the receptacle.

The invention consists of the novel construction and arrangement of the parts and combinations of parts hereinafter more fully set forth in the following specification and pointed out in detail in the appended claim.

In the accompanying drawing:

Figure 1 is a side elevation of my invention.

Fig. 2 is a top plan view of Fig. 1.

Fig. 3 is a vertical section of Fig. 2 on the line E—E.

Fig. 4 is an enlarged detail view of one of the notched projections at the side of the cap.

Referring to the accompanying drawing, forming part of this specification, and in which like reference numerals designate like parts throughout the several views thereof, 1 designates a metal cap having a downwardly projecting crimped flange 2 having a number of projections 3 extending below

said flange 2 each of which is provided with a recess 4 in its under surface below the flange 2. The closure is put on the bottle, jar, or other vessel in any suitable manner and by means of the projection 3 can be readily removed by any suitable tool, or by striking the projection against any object to force the top from the bottle or vessel. The projections 3 consist of two plane faces forming an oblique angle with the circumferential flange and meeting in a downwardly and outwardly inclined ridge. The recesses 4 in the under surface of the projection are for the purpose of receiving a suitable tool and preventing it from slipping off the projection 3 when the closure is being forced off by said tool.

Having thus described my invention, what I claim is:

A closure for bottles, comprising a cap having a downwardly projecting annular crimped flange 2, and a number of projections 3 arranged equidistant around and extending below said annular flange and each having a recess 4 in its under surface below said flange 2, said projections 3 consisting of two plane faces forming an oblique angle with the annular flange and meeting in a downwardly and outwardly inclined ridge.

JAMES W. HENTZ.
